DESIGN FOR A PORTABLE BUILDING

Millson W. Downs, Los Angeles, Calif.

Application June 15, 1942, Serial No. 107,194

Term of patent 7 years

To all whom it may concern:

Be it known that I, Millson Wm. Downs, a citizen of the United States of America, residing at Los Angeles, in the county of Los Angeles, State of California, have invented a new, original, and ornamental Design for a Portable Building, the same constituting a housing for workers and soldiers, of which the following is a specification, reference being had to the accompanying drawing, forming a part thereof.

In the drawing, the figure constitutes a perspective view of my design showing one end and one side thereof, the opposite side thereof being the same as that shown, and the other of the ends thereof is the same as that shown.

I claim:

The ornamental design for a portable building, as shown and described.

MILLSON WM. DOWNS.
